(57)

CLAIM

The ornamental design for a sole for a shoe, as shown and described.

DESCRIPTION

FIG. 1 is a left side view of a sole for a shoe showing the claimed design;

FIG. 2 is a right side view thereof;

FIG. 3 is a rear view thereof; and,

FIG. 4 is a bottom view thereof.

The broken lines in the figures and the area(s) within the broken lines show portions of the sole for a shoe that form no part of the claimed design.

1 Claim, 4 Drawing Sheets
